UNITED STATES PATENT OFFICE.

HAROLD DE OLANETA, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

METHOD OF INCREASING THE LIFE OF DRY CELLS.

Original application filed December 22, 1919, Serial No. 346,694. Divided and this application filed May 3, 1920. Serial No. 378,458.

To all whom it may concern:

Be it known that I, HAROLD DE OLANETA, of New Haven, county of New Haven, State of Connecticut, have invented certain new and useful Improvements in Methods of Increasing the Life of Dry Cells, of which the following is a full, clear, and exact description.

This invention relates to galvanic cells, and more particularly to dry cells.

This application is a division of my application Serial No. 346,694, filed December 22nd, 1919, and pertains more especially to the method of increasing the life of the cell.

In dry cells of the type now found on the market in large numbers, and especially those used for pocket flash lights or hand lamps, the zinc electrode is in the form of a cup in which are contained a carbon electrode with a surrounding body of depolarizing material, and an exciting paste interposed between the depolarizing material and the side wall of the cup. The depolarizing material usually consists of a mixture of manganese dioxid and carbon which is formed into a block or cartridge about the carbon electrode and is contained within an envelope or bag of cheese cloth or the like.

In the manufacture of cells of this type, the paste when placed in the cell ordinarily contains a solution of sal ammoniac, which is the principal exciting agent, and a solution of zinc chlorid, which, owing to its deliquescent nature, serves to keep the paste moist. The depolarizing mixture, consisting of finely divided manganese dioxid and carbon (graphite), is usually moistened with a solution containing ammonium chlorid and zinc chlorid, so as to facilitate the passage of the ions from one electrode to the other through the depolarizing body and paste.

Cells made up in the usual way, with an ammonium-chlorid-containing paste in direct contact with the zinc, are apt to deteriorate considerably before they are placed in use, owing to the fact that, due to local action, the ammonium chlorid commences its attack on the zinc as soon as the parts of the cell are put together. Local action is set up, for example, as a result of the presence of impurities in the zinc, or by reason of differences in the molecular structure of the

same at different parts of the cup. Under present conditions of manufacture and distribution, there is usually a considerable interval between the time when the cell is first assembled and the time when it reaches the consumer for use. It is not uncommon for the cells to remain in the factory a week or longer, owing to delays in packing and shipping. Furthermore, when they leave the factory it takes some time for them to reach the retailer, and, of course, they may remain on the shelf of the retailer for a long period before they are purchased and used. Consequently when a cell is finally put into use, the zinc cup is likely to be considerably eaten away, and the active life of the cell is, therefore, seriously impaired.

One of the primary objects of my invention is to eliminate the above mentioned drawback as far as possible. I provide a cell in which the action of the sal ammoniac on the zinc while the cell is being shipped and while it is on the shelf is avoided to a large extent. The cell of my invention does not have maximum efficiency when first assembled, but it reaches maximum efficiency some time thereafter, in other words, at about the time that it comes into the hands of the user. In this manner the life of the cell in the hands of the user is considerably increased.

Another object of my invention is to simplify and improve the process of manufacturing dry cells of the type indicated. In ordinary methods of manufacture, there are numerous drawbacks and inconveniences arising out of the incorporation of the sal ammoniac and zinc chlorid in the same body, more particularly in the paste. For example, there are difficulties as regards the proper proportioning of the two solutions which are commonly employed. Again, the sal ammoniac-containing paste is difficult to handle in the factory owing to the fact that sal ammoniac is a climbing salt. One of the greatest objections, however, is that when sal ammoniac is incorporated in the paste before the latter is placed in the cell, the paste will not keep for any length of time. It has to be used immediately after being mixed up, as otherwise there is apt to be a formation of mold.

Another object, therefore, of my present invention is to overcome these difficulties and disadvantages incident to the manufacture of the cells.

5 To these and other ends, the invention consists in a method of making a dry cell having a depolarizing body surrounding one electrode and a paste interposed between the depolarizing body and the other 10 electrode, which comprises the incorporation of the principal electrolyte salt in the depolarizing body, but not in the paste, as hereinafter described and claimed.

15 The invention also consists in other steps and novel features, as hereinafter set forth.

The accompanying drawing shows in vertical, central section a dry cell made in accordance with the invention.

20 The cell comprises the usual zinc cup 1 constituting the positive electrode. The negative carbon electrode 2 has tamped about the same a block or cartridge 3 of suitable depolarizing material; and interposed between the side wall of the cup and 25 the depolarizing material is a paste 4. The depolarizing cartridge is usually contained in a bag or envelope 5 of cheese cloth or the like. It is centered in the cup at the bottom by a suitable centering washer 6. At the 30 top of the cell the latter is sealed in any suitable manner, as by a pitch seal 7 on top of a paper washer 8. The carbon electrode is provided with the usual contact cap 9.

35 In carrying out my invention, I provide a paste which is initially devoid of sal ammoniac. The paste is preferably composed of wheat flour or some other cereal, zinc chlorid solution, and a mercury compound. In making up a batch of paste for the manufacture of a number of cells, I mix together, 40 for example, 12.5 kilograms of wheat flour, 50 litres of zinc chlorid solution at 27 Baumé, and 12.5 grams of mercuric chlorid. The ingredients are mixed together until all of 45 the flour is dissolved, and the mass is stirred, while being cooked, until a stiff paste is formed. The cooking is effected before the paste is placed in the cell.

50 The depolarizing body preferably comprises a mixture of manganese dioxid, graphite, and sal ammoniac; for example, in the proportions of 37.5 units of manganese hydrate, 12.5 units of graphite and 10 units of sal ammoniac. These ingredients, which 55 are in a fine state of subdivision, are mixed with water until the mass is plastic and homogeneous, whereupon it is formed into the block or cartridge 3 about the carbon electrode 2 in a manner well understood in 60 the art.

65 The paste will keep for a long time and does not have to be used at once owing to the fact that the zinc chlorid is of an anti-septic nature and acts as a preservative for the vegetable substance, e. g. wheat flour.

The drawbacks incident to the incorporation in the paste of ammonium chlorid, which is a bacterial food, are eliminated.

70 When the cell is first put together, the ammonium chlorid does not immediately commence its attack on the zinc, owing to the fact that it must first traverse the paste. The sal ammoniac passes out only gradually from the cartridge into the paste and to the zinc. Thus the cell is not at maximum efficiency when first assembled, as is ordinarily the case, but reaches maximum efficiency after a definite interval has passed, depending upon the distance between the depolarizing cartridge and the side wall of the zinc 75 cup. For example, with the smaller sizes of cells commonly used for pocket flash lights, the distance which has to be traversed by the sal ammoniac before it reaches the zinc, is such that maximum efficiency is 80 not obtained for a period varying from two weeks to a month. In a larger size, where the sal ammoniac has to traverse a greater distance, the conditions usually obtaining in a freshly made cell do not obtain for approximately three months. Therefore there is likelihood that the cell will not reach its maximum efficiency until about the time that it is placed in use. At any rate the life of the cell in the hands of the consumer is considerably increased owing to the fact that the length of time that the sal ammoniac acts on the zinc previous to the use of the cell, 85 is considerably reduced.

90 In the case under discussion, the sal ammoniac passes outward through the porous envelope 5 of the cartridge into the paste and to the zinc, and the zinc chlorid in the paste passes into the cartridge; but it will be apparent that the invention is 95 not limited to a cell wherein the depolarizing cartridge has a porous envelope. Regardless of whether or not an envelope is employed, the paste takes up sal ammoniac from the cartridge and the cartridge takes 100 up zinc chlorid from the paste. Furthermore, these substances are distributed as needed for the best working of the cell. Heretofore, in manufacturing cells wherein the paste contained both zinc chlorid and 105 ammonium chlorid, there was considerable difficulty in properly proportioning these two substances. It was necessary to weigh the substances and to compare the density of their solutions, etc., and even where great 110 care was exercised in compounding the paste, the results were not always satisfactory. In the present case, however, the process of manufacture is considerably 115 simplified, because it is not necessary to mix the chlorids and because such great care in attempting to reach a definite proportion of the ingredients is unnecessary. With my improved cell, the ammonium chlorid is fed or supplied to and taken up 120

by the paste in the proper quantity for the best working, and the zinc chlorid is fed to and taken up by the cartridge in the proper quantity for best working, regardless of the quantities of those substances which are used, within certain limits.

The chlorid of mercury in the paste serves the usual purpose of amalgamating the zinc.

10 So far as manufacturing advantages are concerned, it will be understood that a paste made in the manner herein described, which is devoid of ammonium chlorid when first compounded, will keep better and is much easier to handle than a paste in which ammonium chlorid is incorporated. The ammonium chlorid not only starts the forming of mould, but climbs out of the paste and over the containing vessels and utensils 20 employed in the storage and handling of the paste, thus causing much inconvenience. Owing to these drawbacks, and the tendency of the sal ammoniac to dry up the paste, it has been impossible heretofore to 25 use paste prepared any considerable length of time in advance of the time when it was placed in the zinc cups, and there was, therefore, considerable waste.

While my improved cell ordinarily does 30 not reach its maximum efficiency until some time after it has left the factory, it can be readily brought to maximum efficiency by placing it in a closed circuit. When the cell is used for lighting a small lamp, for 35 example, the passage of electric current through the cell has the effect of hastening the passage of the electrolyte, viz, the sal ammoniac, to the zinc. Of course, the zinc chlorid in the paste serves as an electrolyte to a sufficient extent to establish a current through the cell when the circuit is closed, and such current has the effect of drawing out the sal ammoniac from the 40 depolarizing body so that the former will quickly reach and act on the zinc for the establishment of a strong current. While, 45 therefore, cells made in accordance with the present invention meet the present conditions of slow distribution to the consumer, this advantage is not coupled with any 50 appreciable lack of efficiency in the cell as freshly assembled.

The mercuric chlorid used in the paste as an amalgamator is of an antiseptic or 55 preservative character, as well as the zinc chlorid, and hence all of the materials added to the wheat flour or the like tend to preserve the same and arrest decomposition.

While I have referred herein to sal ammoniac as being the principal exciting 60 agent and to zinc chlorid as a paste moistening agent having a certain electrolyte value; it is to be understood, of course, that I do not limit myself in all aspects of the invention to the use of these particular salts, or,

in fact, to the employment of two distinct salts.

Various changes may be made in the details of the procedure and in the composition and arrangement of parts as herein 70 described, without departing from the scope of my invention as set forth in the claims.

I do not claim herein the cell per se, as claimed in the parent application, Serial No. 346,694; nor do I claim herein the particular 75 composition of the paste, as claimed in my application, Serial No. 378,457; nor do I claim herein the specific composition of the depolarizing body, as claimed in my application, Serial No. 360,553. 80

What I claim is:

1. The method of making a dry cell having a depolarizing body, a surrounding paste, and inner and outer electrodes, which comprises incorporating substantially all of 85 the electrolyte material in the depolarizing body.

2. The method of making a dry cell having a depolarizing body, a surrounding paste, inner and outer electrodes, and a sal ammoniac electrolyte, which comprises incorporating all of the sal ammoniac electrolyte 90 in the depolarizing body, and providing a paste which is substantially devoid of sal ammoniac. 95

3. The method of increasing the life of dry cells of the type having a zinc cup and a contained electrolyte, which comprises so locating the electrolyte with reference to the cup that the former does not come into contact with the latter until some time after the assemblage of the cell. 100

4. The method of increasing the active life of a dry cell having a zinc cup and a sal ammoniac electrolyte, which consists in 105 postponing any contact of the electrolyte with the zinc until some time after the cell is assembled.

5. The method of increasing the life of a dry cell having a zinc cup and a sal ammoniac electrolyte, which consists in initially 110 separating all of said electrolyte and the zinc cup and bringing the electrolyte into contact with the cup during the operation of the cell. 115

6. The method of increasing the life of a dry cell having a zinc cup and a contained electrolyte, which consists in initially separating the electrolyte from the cup by a surrounding paste and bringing the electrolyte 120 into contact with the cup through natural causes some time after the cell is assembled.

7. The method of increasing the life of a dry cell having a metal cup and a contained electrolyte, which consists in postponing the contact of the electrolyte with the cup by locating a paste between it and the cup and utilizing the diffusive property of the electrolyte for bringing about contact thereof 125 130

with the cup after the cell has been assembled for a certain length of time.

8. The method of increasing the life of a dry cell having a zinc cup and an activating electrolyte, which consists in locating such electrolyte at some distance from the surface of the cup and utilizing the infiltrating property of the electrolyte for bringing about attack on the zinc some time 10 after the cell has been assembled.

9. The method of increasing the life of a dry cell having a cup and a contained electrolyte, which consists in surrounding the electrolyte by a relatively inert paste and 15 employing the diffusion of the electrolyte to bring about the action thereof on the cup.

10. The method of increasing the life of a dry cell having a zinc cup and an ammonium chlorid electrolyte, which consists 20 in utilizing the diffusive property of the electrolyte for bringing about a retarded attack of the same on the zinc.

11. The method of increasing the life of a dry cell, which comprises postponing the 25 attack of the electrolyte on the zinc by utilizing the infiltrating property of the electrolyte for bringing about a retarded contact.

12. The method of bringing about a retarded contact of the electrolyte with the 30

cup in a dry cell, which consists in utilizing the diffusive property of the electrolyte to carry it slowly over an intervening space.

13. The method of increasing the life of a dry cell, which consists in causing the activating electrolyte to be diffused through a 35 paste before contacting with the zinc.

14. The method of increasing the life of a dry cell, which consists in locating the activating electrolyte within the zinc cup 40 at some distance therefrom and causing it to filter slowly through a relatively inert paste into contact with the cup.

15. The method of increasing the life of a dry cell, which consists in utilizing the diffusion of the electrolyte to bring about a retarded action of the latter on the metal electrode.

16. The method of increasing the life of a dry cell having a zinc cup and a contained 50 electrolyte, which consists in initially separating such electrolyte from the zinc cup and bringing the former into contact with the latter some time after the cell has been assembled by the infiltration of such electrolyte through a relatively inert paste.

In witness whereof, I have hereunto set my hand on the 30th day of April, 1920.

HAROLD DE OLANETA.
